DESIGN FOR A DOMESTIC IRONING MACHINE

Donald W. Haney, Binghamton, N. Y., assignor
to Nineteen Hundred Corporation, Bingham-
ton, N. Y., a corporation of New York

Application June 30, 1934, Serial No. 52,404

Term of patent 14 years

To all whom it may concern:

Be it known that I, Donald W. Haney, a citizen of the United States, residing at Binghamton, in the county of Broome and State of New York, have invented a new, original, and ornamental Design for a Domestic Ironing Machine, of which the following is a specification, reference being had to the accompanying drawing, forming a part hereof, in which:

Figure 1 is a front elevation of a domestic ironing machine embodying my new design, and

Figure 2 is an end elevation of the machine of Figure 1 as viewed from the right.

I claim:

The ornamental design for a domestic ironing machine, as shown.

DONALD W. HANEY.
